(57) **CLAIM**

The ornamental design for a glove, as shown and described.

DESCRIPTION

FIG. 1 is a perspective view of a glove showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the glove where the glove is in a configuration of use.

The broken lines showing a hand and an arm in FIG. 9 depict environmental structure and form no part of the claimed design. All other broken lines in the drawings depict portions of the glove and form no part of the claimed design.

1 Claim, 9 Drawing Sheets
